UNITED STATES PATENT OFFICE.

JOHN K. SHANAMAN, OF ANNVILLE, PENNSYLVANIA.

ARTIFICIAL LIMB.

SPECIFICATION forming part of Letters Patent No. 740,476, dated October 6, 1903.

Application filed April 22, 1903. Serial No. 153,816. (No model.)

To all whom it may concern:

Be it known that I, JOHN K. SHANAMAN, a citizen of the United States, residing at Annville, in the county of Lebanon and State of Pennsylvania, have invented certain new and useful Improvements in Artificial Limbs, of which the following is a specification.

My invention relates to artificial limbs, and more particularly to artificial legs having movable joints, the object being to provide for an ankle movement controlled from the knee.

The invention consists of certain novel constructions, combinations, and arrangements of parts, all of which will be hereinafter more particularly set forth and claimed.

The nature, characteristic features, and scope of the invention will be more clearly understood from the following description, taken in connection with the accompanying drawings, forming a part hereof, wherein—

Figure 1 is a perspective view of an artificial leg constructed in accordance with my invention. Fig. 2 is a view, principally in section, of the foot, showing the ankle and knee connections. Fig. 3 is a view in perspective of the upper portion of the leg proper. Fig. 4 is a detail side view of the knee and ankle connections, and Fig. 5 is a perspective view of the connections.

In the drawings, 1 represents the attaching thigh-socket; 2, the leg proper; 3, the ankle; 4, the pivoted foot; 5, the hinged toe portion; 6, the operating - rods, and 7 the joints between the ankle and foot. The attaching thigh-socket 1 may be constructed of any desired material and is perfectly slit, as at 8, and provided with lacing-apertures 9, whereby it may be secured in position upon the amputated limb. This thigh-socket is provided upon diametrically opposite sides with pendent hinged members 10. One or both of said hinged members is or are provided with eccentric parts or members 11, to which are hinged the forked upper ends of the connecting-rods 6. The rods 6 are located between the skeleton frame 2, constituting the leg proper, and a sleeve 12, which latter may be made of the same material as the attaching-socket 1. The ankle 3 constitutes a part of the leg proper, as will be observed upon reference to Fig. 1. The joints 7 comprise

the bolts 13, having screw-threaded ends secured by nuts 14 and having the apertured heads 15, in which is secured a pin 16. The pin 16 has hinged thereon the bolts 17, which penetrate corresponding openings in the foot and are secured by nuts 18. The foot 4 is socketed, as at 19, to accommodate the shouldered part 20 of the ankle.

The connecting-rod 6 passes through a passage or opening 21 in the ankle 3 and is pivotally attached to an arm or member 22, which is in turn pivoted in a bracket 23, secured to the base of the ankle. The arm 22 is provided at its end with a pivotal bolt 24, which is accommodated in a bore 25, arranged to one side of the foot. As clearly shown in Fig. 2, the bore 25 is served with a lining 26 to save wear of the parts, and said lining 26 preferably consists of brass.

27 is a coil-spring which surrounds the bolt 24 and serves to maintain the proper position or regulation of the foot in respect to the ankle. 28 is a nut for securing the foot in respect to said bolt.

When the amputated limb is advanced, the movement of the eccentric member or members 11 will cause the connecting-rods 6 to tip the foot so that it will strike the ground firmly with the toe depressed, whereas the reverse movement of the limb will cause the toe to be elevated, so that in swinging forward for the next succeeding step said toe will clear all slight obstacles upon the pavement. It will also be observed that a perfectly natural movement of the foot is secured by the pivotal connection of the knee-joint. Further, the foot is moved while passing through the air, and the action of the spring 27 prevents a shaking movement of the foot and also any rattling of the same.

It will be obvious to those skilled in the art to which the invention appertains that modifications may be made in details without departing from the spirit and scope of same. Hence I do not limit myself to the precise construction and arrangements of parts hereinbefore described; but,

Having described the nature and objects of the invention, what I claim as new, and desire to secure by Letters Patent, is—

1. In an artificial leg, the combination of an attaching thigh-socket, a leg and its ankle,

an eccentric member carried by one of said hinged members, a foot hinged to the ankle of said leg, an operating-rod interposed between said eccentric member and the foot, an arm having its rear end pivoted to the bottom of the ankle, and a spring-bolt pivoted to the front end of said arm, substantially as described.

2. In an artificial limb, the combination of an attaching thigh-socket, a leg, pendent hinged members connecting the socket and leg, an eccentric member carried by one of said hinged members, a foot hinged to said

leg and having a bore or passage, a brass tubular lining or sleeve in said passage, a spring-bolt in said sleeve, a connecting-rod attached at one end to said eccentric member, and a pivotal arm connecting said rod and spring-bolt, substantially as described.

In testimony whereof I affix my signature in presence of two witnesses.

JOHN K. SHANAMAN.
